DUMP BODY

Thomas Eugene Wright, Jersey City, N. J.

Application September 2, 1931. Serial No. 560,849

6 Claims. (Cl. 298—11)

This invention relates to a dump body of that type adapted to be tilted to different angles to meet the requirements for dumping the load. It is more especially an improvement upon the structure covered by my copending application #456,774, filed May 28, 1930.

One of the objects is to simplify and otherwise improve upon the means provided for regulating the angle of the body when in dumping position, said means being readily shiftable prior to the elevation of the body to insure its movement to desired position.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

25 In said drawings:

Figure 1 is a side elevation partly broken away, showing the body in its lower or normal position.

Figure 2 is a similar view showing the body tilted for a low dump.

30 Figure 3 is another view like Figures 1 and 2 showing the body elevated for a high dump.

Figure 4 is a section on line 4—4, Figure 3.

Figure 5 is a section on line 5—5, Figure 3.

Figure 6 is a perspective view of one side of 35 the side beams of the secondary supporting frame.

Figure 7 is a perspective view of the latch rods.

Figure 8 is a perspective view of one of the restraining members.

40 Figure 9 is a detail view of a thrust link.

Referring to the figures by characters of reference, 1 designates a truck chassis supporting a frame 2 having channeled beams 3 which can be used as a track for rollers 4 at the ends of a transverse shaft 5. A drum 6 operated by any suitable means, is supported transversely of the beams 3 and is used for winding and unwinding chains, cables, or other suitable flexible members 7 each of which is secured at one end to the beams 3 as at 8, and at its other end to the drum. These are looped around the shaft and are adapted to move it when they are wound on the drum.

The main supporting frame 9 is pivotally anchored at its rear end to the beams 3, as shown

at 10. The front end of this frame is slidably and pivotally engaged by slotted brackets 11 extending downwardly from the front end of the body 12.

A secondary supporting frame 13 is extended 60 through frame 9 and pivotally connected thereto between its ends by a transverse pivot rod 14. The rear end of frame 13 is pivotally connected to the rear end portion of the body 12 as shown at 15.

65 Thrust links 16 connect shaft 5 to the rod 14 and also extending from shaft 5 are restraining members 17 one of which has been shown in detail in Figure 8. Each restraining member includes a bar 18 having a longitudinal slot 19 in 70 that end portion remote from shaft 5. This bar projects between the parallel sides of an elongated yoke 20 formed by folding a metal strip. The loop loosely straddles one side of the frame 13 and has notches 21 in its rear edges located 75 where they can receive bar 14 when the restraining member is shifted to one extreme position. A pivot bolt 22 extends through yoke 20 and slot 19 and serves to pivotally and slidably connect the parts 18 and 20.

80 A stud 23 is extended upwardly from each yoke 20 and is secured loosely in one end of a latch rod 24 extending along the top of frame 13. Each rod can be provided with a series of notches 25 any one of which is adapted to receive a lug or keeper 26 extending upwardly from one side of frame 13. The rods are connected by a cross rod 27 as shown in Figure 7, but it is to be understood that, if desired, the rods can be separate from each other and separately actuated.

85 Normally the body 12 rests on frame 9 and said frame, in turn rests on beams 3. The secondary frame 13 is normally positioned between the sides of frame 9 and the restraining member 90 is partly folded. These positions have all been shown in Figure 1.

95 Should it be desired to make a low dump by lifting the front end only of body 12, the operator would first grasp the rods 24 or rod 27 and by means thereof pull the restraining members 17 rearwardly along the sides of frame 13 until rod 14 is seated in notches 21. Thus when the shaft 5 is drawn toward drum 6 the links 16 will thrust upwardly on rod 14 and frame 9 and as 100 frame 13 is unrestrained, it will not shift relative to frame 9. Consequently, the body 12 will remain flat on frame 9 and tilt therewith as in Figure 2.

105 Should a high dump be desired the operator, 110

before raising the parts from the positions shown in Figure 1, shifts the restraining members 17 away from rod 14 until brought to a desired distance from said rod 14. The angle to which the 5 elevated body 12 will be brought will depend upon the distance of the restraining members 17 from rod 14. After these members are properly adjusted the rods 24 are placed in engagement with keepers 26. One such position is shown in 10 Figure 1.

Following the adjustment described the thrust members or links 16 are actuated to raise the main frame 9. Frames 9 and 13 will move together as the members 17 unfold or straighten 15 out. Immediately thereafter these members will hold back on the front portions of frame 13 so that as rod 14 and frame 9 continue to move upwardly, the rear end of frame 13 will also be 20 swung upwardly, thereby lifting the back end of body 12 from frame 9 as in Figure 3. As before stated, the angle of the hoisted body 12 relative to frame 9 will depend upon the distance between members 17 and rod 14.

In every instance the body and other parts can 25 be lowered by gravity to the positions shown in Figure 1 simply by unwinding the connections 7 from drum 6.

What is claimed is:

1. The combination with a truck structure and 30 a body, of crossed pivotally connected main and supplemental supporting frames, a pivotal connection between the main frame and the truck structure, movable connections between said frames and the body, means movably engaging 35 the truck structure for exerting a thrust against said frames at their point of connection to each other thereby to raise the frames and body, a foldable restraining element pivotally connected to the thrust means and slidably connected to 40 the supplemental frame, and means for adjusting said element toward and from the point of connection between the frames prior to the elevation of the frames.

2. The combination with a truck structure and 45 a body, of crossed pivotally connected main and supplemental supporting frames, a pivotal connection between the main frame and the truck structure, movable connections between said frames and the body, a shaft, means for moving 50 the shaft along the truck structure, a connection for transmitting thrust from the shaft to the frames at their point of crossing, a foldable restraining element pivoted on said shaft and movable along the supplemental frame, and means 55 for adjusting said element along said supplemental frame.

3. The combination with a truck structure and 60 a normally lowered body, of pivotally connected

crossed frames interposed between the structure and body, one of the frames being connected to the structure and body and the other frame being connected to said body and having a free end portion, a thrust means movably supported on the structure and connected to the frames, and foldable restraining means movable with the thrust means and adjustable along said free end portion while the body is lowered.

4. The combination with a truck structure and 80 a body, normally in lowered position, of pivotally connected crossed frames interposed between the structure and the body, one of the frames being connected to the structure and body and the other frame being connected to said body and having a free end portion, a thrust means 85 movable on the structure and connected to the frames, foldable restraining means adjustable relative to the lowered body along said free end portion, and movable with the thrust means, and means for fastening said restraining means in position coaxial with the pivotal connection of the frames and at predetermined distances therefrom.

5. The combination with a truck structure and 90 a body, of pivotally connected crossed frames interposed between the structure and body, and foldable to position the body in lowered position on the structure, one of the frames being connected to the structure and body and the other frame being connected to said body and having a free end portion, thrust means movable 95 along the structure and connected to the frames, foldable restraining means movable with the thrust means and adjustable along said free end portion, means shiftable relative to the body while the body is in said lowered position for fastening said restraining means in position coaxial with the pivotal connection of the frames and at predetermined distances therefrom, said 100 means including a latch rod extending from the restraining means, and a keeper on one of the frames adjustably engaged by the rod.

6. The combination with a truck structure and 105 a body normally resting thereon, of crossed pivotally connected frames between the structure and body, one of the frames being movably connected to the structure and body and the other frame having one end connected to the body and its other end free, movable thrust means supported on said structure and to actuate the frames 110 at their point of crossing to raise the body, and a foldable restraining element movable with the thrust means, said restraining means being adjustable along said free end portion toward or 115 from the point of crossing of the frames while the body is in normal position.
